UNITED STATES PATENT OFFICE

2,030,302

SPINNING TOP

Walter L. Jones, Kenmore, N. Y.

Application May 9, 1933, Serial No. 670,080
Renewed July 6, 1935

5 Claims. (Cl. 46—60)

This invention relates to certain new and useful improvements in spinning tops or toys or what are commonly known as diablos.

One of its objects is to provide a toy of this character which is not only simple and inexpensive in construction but which is so designed as to be soft and yieldable to render it non-breakable and harmless to the user and at the same time sufficiently rigid to permit it spinning at high speeds.

Another object of the invention is to provide a spinning top which is made of rubber and shaped to provide hollow, air tight, substantially bell-shaped ends.

15 In the accompanying drawing:—

Figure 1 is a side elevation of the spinning top embodying my invention. Figure 2 is a longitudinal section thereof taken on line 2—2, Figure 1. Figure 3 is a detached perspective view of the central core or reinforcing element of the top.

20 Similar characters of reference indicate corresponding parts throughout the several views.

Heretofore spinning tops of this character or diablos have been made from solid material, usually wood, and are therefore subject to breakage when falling from a reasonable height and are dangerous to the user or users, it being understood that these tops are usually spun on a cord connected at its ends to two sticks held in the hand of the user and after the top attains a high spinning speed the same is projected high into the air and as it comes down is caught again by the user or is passed to and fro to another party equipped with the cord and sticks.

35 My improved spinning top is made of rubber or like elastic or flexible material and consists of a reel or spool-like body of substantially double bell-like shape having oppositely facing frusto-conical portions 10 terminating at their enlarged ends in rounded or substantially globular air tight heads 11. The portions 10 and heads 11 jointly form hollow sections, the walls 10 being preferably comparatively thick and the walls of the heads being comparatively thin and readily yieldable or shock-absorbing when subjected to impact. These hollow sections are preferably mounted on a spool-like body or reinforcing element consisting of metallic hub-sections 12 of substantially frusto-conical shape with their smaller ends disposed in fixed abutting relation to provide centrally of the top, or at its point of balance, a string-receiving groove 13. For the purpose of properly centering these hub-sections and assisting in holding them together, I employ a screw stud 14, as seen in Figure 2. The hollow rubber portions 10, 11 of the top may be applied to the companion hub-sections by a pressure-blown molding process or in any other appropriate manner, the walls of said sections having openings 15 therein in which the rubber portions are vul-

canized and securely held. As shown in Figure 3, each of the hub-sections 12 is provided intermediate its ends with an annular shoulder or offset 16 resulting in the provision of stepped walls, the rubber portion 10 enclosing or embracing the outer wall and terminating at or flush with the adjoining end of such resulting inner wall, as depicted in Figure 2.

5 By constructing the top in this manner, a perfectly balanced, hollow air tight structure is provided which can be spun at high speeds and which possesses sufficient yieldability or shock-absorbing qualities to render it harmless in use, even if one should be accidentally struck by it, and danger against breakage is eliminated.

15 I claim as my invention:—

1. A device of the character described, comprising a rigid open-ended, spool-like body having openings therein, and hollow rubber heads applied to and enclosing the open ends of said body and having portions extending through and interlocking with said body-openings.

2. A toy of the character described, comprising a substantially spool-like metallic body having a central, bridge wall and an annular string-receiving groove in the plane of said wall, the outer marginal edges of said body having openings therein, and hollow-symmetric end portions of elastic material disposed about and projecting axially beyond said body and having portions extending through said body-openings in permanent vulcanized relation thereto.

3. A toy of the character described, comprising a pair of substantially cone-shaped elements disposed in opposing axial relation with their tapered ends in abutting relation to provide an annular string-receiving groove, and hollow rubber heads molded to said cone-shaped elements and projecting axially beyond the same, the flared ends of said elements having openings 40 therein through which the adjoining portions of the rubber heads extend during the molding process to permanently unite the heads to said elements.

4. A toy of the character described, comprising a rigid spool-like body open at its ends and having openings therein adjacent the edges thereof, and substantially bell-shaped heads of rubber molded to and enclosing the open ends of said body and having portions extending through and interlocking with said body-openings.

5. A device of the character described, comprising a substantially hollow, hub-like member having openings therein adjacent an edge thereof, and a hollow rubber head molded to and enclosing that area of said hub-like member containing said openings and having portions thereof extending through and interlocking with said openings.
